METAL EXTRUSION PRESS AND METHOD OF OPERATION

Edgar W. MacKnight, Bayonne, N. J., assignor to
General Cable Corporation, New York, N. Y.,
a corporation of New Jersey

Application December 19, 1933, Serial No. 703,057

22 Claims. (Cl. 207—2)

This invention relates to metal extrusion presses and the method of operating such presses. More particularly the invention is concerned with presses for extruding metal sheaths on electrical cables. Ordinarily, cable sheaths are made of lead or an alloy of lead. It is an object of this invention to provide improved apparatus for extruding metal, and also to provide an improved method of operating such apparatus in which the metal to be extruded is not exposed to air or other gases. Other objects and advantages of the invention will appear hereinafter.

The invention will be best understood from the following description when read in the light of the accompanying drawings illustrating certain specific embodiments of the invention.

In the drawings:

Fig. 1 is an elevation, partly diagrammatic, of a press for extruding cable sheaths, and of the associated metal pot;

Fig. 2 is a top plan view of the bracket 125 shown in Fig. 1;

Fig. 3 is an enlarged vertical section through the upper end of the press cylinder, the lower end of the press ram and the stuffing box connecting these two members;

Fig. 4 is a section substantially on the line 4—4 of Fig. 3;

Fig. 5 is an enlarged vertical section through the upper end of the press ram and the canopy of the press;

Fig. 6 is an enlarged vertical section through a portion of the metal melting pot, showing the metal measuring and pumping device;

Fig. 7 is a section substantially on the line 7—7 of Fig. 6;

Fig. 8 is a section substantially on the line 8—8 of Fig. 6;

Fig. 9 is a vertical section through a valve which, in some cases, may be substituted for the metal measuring and pumping device shown in Fig. 6;

Fig. 10 is a somewhat diagrammatic showing of apparatus used, for example, with the valve shown in Fig. 9 for measuring and indicating continuously the amount of metal extruded from the press in an extrusion operation, and also the amount of metal entering the press during a charging operation; and

Fig. 11 is a view of the indicator dial substantially on the line 11—11 of Fig. 10.

In sheathing electrical cables with metal there are two types of vertical presses in general use. In one of these the press cylinder is stationary and the press ram moves, while in the other the

press ram is stationary and the press cylinder moves. The present invention is most easily adapted for and is illustrated herein with reference to a press in which the ram is stationary.

The actual extrusion of metal is not continuous in either type of press for the reason that it is necessary to separate the ram and the cylinder and recharge the cylinder with metal when a majority of the original charge of metal has been extruded from the cylinder. In recharging, 10 the cylinder is filled with molten metal, and then it is necessary to wait until the metal cools sufficiently to solidify before the extrusion operation can be continued.

Heretofore it has been the common practice in 15 charging a press cylinder to separate the cylinder and the ram, and then to fill the cylinder with molten metal from a nearby melting pot by opening a valve at the bottom of the pot and permitting metal to flow down an inclined trough, the 20 lower end of which has been moved over the open end of the press cylinder. When the cylinder has been filled with molten metal the valve at the bottom of the pot is closed, and an effort is made to remove the dross on the top surface 25 of the metal in the cylinder either by flotation or by skimming. The ram is moved downwardly to seal the charge and then it is necessary to suspend operations until the molten metal has solidified. After solidification of the charge the 30 extrusion operation may be continued.

In operating presses as described above, impurities are accumulated by or formed in the molten metal, and also on the exposed surface of the hot metal slug remaining in the cylinder, and 35 on the thin layers of hot metal on the surfaces of the cylinder and ram. Exposure of the molten metal to the air as it issues from the melting pot and flows through the trough to the press cylinder is accompanied by oxidation of the metal. 40 This oxidation results in the formation of dross which is carried into the press cylinder. The upper surface of the slug left in the cylinder at the completion of an extrusion operation also begins to oxidize as soon as the ram leaves it on its 45 up-travel. Likewise the thin film of metal on the inner surface of the cylinder and the end of the ram oxidizes and finds its way into the charge. This oxidized film tends to prevent perfect welding of the new charge, and while a portion of the 50 oxide may float to the top and be skimmed off, a part of it will remain in the charge. This oxide may reduce the strength of the bond in the cable sheath. Furthermore, some metal may 55 cling to the trough at the completion of a charg-

- ing operation. Such metal will oxidize in the air and build up into large particle sizes which will be carried into the cylinder with the molten metal during the next charging operation.
- 5 In charging a press in the manner just described the metal which runs into the cylinder strikes the relatively cold wall of the cylinder and freezes in an irregular lump. The surface of this lump films over instantly and is continuously spattered with more hot metal, forming a larger lump containing oxide and gas bubbles which eventually must appear in the cable sheath. These entrapped air or gas pockets are compressed to very small size during the extrusion operation, and expand again after passing out of the die. If the pocket is near the surface of the sheath it will explode outward and perhaps may be discovered and repaired, but it is just as likely that the pocket will occur adjacent to the inner surface of the sheath and burst inwardly, to the detriment of the cable insulation, as well as the sheath. Also there is some danger of carrying metallic oxide and other dirt from the melting pot and trough into the cylinder.
- 20 According to the present invention a commercially practicable method and apparatus is provided for extruding cable sheaths, in which oxidation of the slug remaining in the cylinder prior to a charging operation is prevented, and in which molten metal passes from the melting pot to the press cylinder without exposure to the air or any other gas at any point during its movement. Furthermore the inner surfaces of the cylinder and lower end of the ram, both of which come in contact with the metal, are not exposed to the air or other gas, and are therefore free from oxides.
- 25 Referring first to Fig. 1, the vertical columns 21, four in number, support near their upper ends the press canopy 22, from which depends the press ram 23. The ram 23 enters the upper end of the press cylinder 24. Secured on the upper end of the cylinder 24, as by means of the screws 25, is a stuffing box 26 which surrounds the ram. This stuffing box comprises a seal preventing access of air into the cylinder, while permitting relative movement between the ram and the cylinder.
- 30 In the illustrative embodiment the cylinder 24 rests on a layer of heat insulation 27, on top of a flow plate 28, which in turn is supported on the die block 29. However, the cylinder may rest directly on the die block 29, either or both the insulation and the flow plate being omitted. The die block 29 has a horizontal die opening 30 through which the cable passes during the sheathing operation. The die block rests on the upper end of the hydraulic press plunger 31 which may be moved up and down under the action of hydraulic press mechanism not shown here.
- 35 The construction of the lower end of the press ram 23 and of the stuffing box 26 will be better understood by referring to Fig. 3. The stuffing box comprises the ring-like casting 26 having spaced around its periphery a plurality of holes to receive the screws 25 by means of which it is secured on the upper end of the cylinder 24. An air-tight joint between the top surface of the cylinder end and the stuffing box is secured by means of the packing ring 32, for example asbestos, positioned in an annular groove on the lower face of the casting 26. When the screws 25 are turned down this packing is compressed and an air-tight joint is established.

The central opening through the casting 26 conveniently is large enough to permit moving it over the lower end of the ram 23. As will appear hereinafter, the lower end of the ram 23 preferably is slightly larger in diameter than the main body of the ram. The central opening through the casting 26 has a shoulder supporting the packing gland ring 33. The gland ring 33 has a sliding fit with the main body of the ram and conveniently may be formed in two pieces to permit assembly about the ram in the stuffing box. Desirably the lower edge of the gland ring 33 is inclined upwardly away from the ram so that when the press cylinder is moving away from the ram any metal which might have escaped from the cylinder around the lower end of the ram will be shaved off of the ram, thereby protecting the stuffing box packings.

Surrounding the ram and resting on the gland ring 33 are annular packings 34, for example asbestos. Over the packings 34 is the gland 35, also conveniently formed in two pieces to provide a sliding fit with the ram. The gland 35 is forced downwardly to compress the packings 34 between the stuffing box 26 and the ram 23 by means of the ring 36 and the screws 37.

The arrangement of the stuffing box just described provides an air-tight joint between the upper end of the press cylinder and the press ram, but does not interfere with free movement between the cylinder and ram in the normal operation of the press.

Means are provided for evacuating the space between the press cylinder and the press ram under the stuffing box. As shown in the drawings, a pipe 38 is secured in an opening through the wall of the casting 26, and this pipe is connected to evacuating apparatus, for example a pump, not shown. By maintaining a high vacuum within the press cylinder under the ram, oxidation of the slug of metal remaining in the cylinder during a charging operation, and of the molten metal with which the cylinder is charged, are eliminated. Furthermore, the formation of gas pockets or bubbles in the charge is prevented.

The ram 23 has a longitudinally extending central opening 41 which is enlarged for a short distance at the lower end of the ram as shown at 42 in Fig. 3. This enlarged opening 42 is screwthreaded to receive the threaded hub 43 of the end block 44 for the ram. This end block has a close sliding fit with the bore of the cylinder, and conveniently is provided with spanner wrench holes 45 to facilitate securing it into position.

The end block 44 has a shoulder central opening, the lower portion of this opening flaring outwardly, as shown at 46, at an angle of preferably about 45 degrees to provide a valve seat.

Mounted in the upper portion of the end block 44, and supported on the shoulder, is a tubular metal member 47. The member 47 preferably is flanged at its lower end, and this flange 48 may be separated from the shoulder in the block 44 by means of thermal insulation 49. This insulation 49 conveniently is placed under compression, as by means of the tube 50 loosely surrounding the member 47 and bearing on the outer edge of the flange 48. The tube 50 conveniently is pressed downward by means of a ring 51 and the screws 52 passing therethrough and entering the hub 43.

The wall of the member 47 desirably is made fairly thin to insure correct heating, as will appear more fully hereinafter. For this reason it

may be desirable to reinforce the wall as by means of the surrounding circumferential rings or bands 53.

The lower portion of the member 47 adjacent to its flanged end is somewhat reduced in diameter as compared to the main body of the member. Loosely mounted in the opening through the end block 44 is a valve stem 54 whose upper end desirably is round or pointed, and provided with a spider head having arms 55 which loosely engage the inner surface of the member 47 and guide the movement of the valve stem up and down. The arms 56 also limit downward movement of the valve stem by reason of their engagement with the constricted portion of the member 47.

The lower end of the valve stem 54 which extends downwardly beyond the shoulder in the end block 44 conveniently is screwthreaded to receive the valve 56. It will be apparent that when the valve is moved upwardly it will engage the valve seat 46, thereby closing the passageway between the press cylinder and the member 47, and preventing flow of metal outwardly from the cylinder. When the valve stem moves downwardly this passageway will be open, permitting flow of molten metal into the cylinder.

Preferably, the valve 56 extends downwardly beyond the lower face of the end block 44 somewhat in the manner shown in Fig. 3. This extension of the valve into the press cylinder constitutes a means whereby the operation of the valve may be controlled automatically by the charge of metal in the cylinder in response to relative movement between the cylinder and the ram. While metal is being extruded from the press the valve is forced upwardly in the valve seat by the pressure in the cylinder and becomes firmly embedded in the upper end of the charge of metal in the cylinder. When movement between the cylinder and the ram is reversed for the purpose of recharging the cylinder with molten metal the grip of the metal on the lower end of the valve 56 is sufficient to pull the valve and valve stem 54 downwardly, thereby opening the valve before the lower end of the valve breaks free from the metal slug.

Thus it will be seen that in the course of normal operation of the press the valve in the lower end of the ram will be operated automatically in response to relative movement between the press cylinder and the press ram. As the cylinder and ram move toward each other the valve will be closed, and as the cylinder and ram separate the valve will be opened.

Passage of metal with which the press is charged into the threaded union between the valve 56 and the valve stem 54 under the extremely high extruding pressure conveniently may be eliminated by boring out the lower end of the valve to a slightly larger diameter than the diameter of the valve stem, and by setting in this enlarged opening a plug 57.

The upper end of the tubular member 47 is closed by means of a shouldered metal plug 61, which desirably tightly engages the inner wall of the member 47. This plug 61 has a downwardly tapered central opening which receives the tapered lower end of a pipe 62 extending upwardly through the longitudinal opening 41 in the ram 23.

Referring now to Fig. 5, the pipe 62 desirably is supported against buckling in its passage upwardly through the press ram and canopy. Conveniently this support takes the form of an in-

sulating bushing 63 surrounding the pipe where the pipe emerges from the ram into the vertical opening 65 in the canopy. The insulating bushing 63 fits loosely about the pipe 62 to permit evacuation of the annular space in the ram 5 through the upper opening in the canopy. The insulating bushing 63 may be held in place by means of a metal ring 64.

The vertical opening 65 in the press canopy is closed at its upper end as by means of a metal 10 plate 66 secured to the canopy with screws 61. Between the canopy and the plate 66 is a compression packing 68 to insure an air-tight joint. The pipe 62 passes outwardly of the canopy through a stuffing box an enlarged central 15 opening in the plate 66.

Secured in this opening in the plate 66 is a cup member 69 containing an insulating packing surrounding the pipe 62. Conveniently this packing may comprise asbestos board bushings 70 between which is a layer 71 of asbestos packing. The packing is maintained under compression, thereby sealing the passage between the pipe 62 and the cup 69, as by means of a plate 72 loosely surrounding the pipe and forced downwardly 25 against the upper bushing 70 by the screws 73.

It will be apparent from the foregoing description that by means of the stuffing box the joint between the pipe 62 and the canopy 22 may be made airtight, and that the pipe 62 may be 30 inserted or removed merely by loosening the stuffing box connection at the top of the canopy.

A tight connection between the lower end of the pipe 62 and the plug 61 is maintained by pressing the pipe downwardly so that its lower 35 end engages the aperture in the plug 61 with a tight wedging action. Conveniently, this downward pressure on the pipe 62 may be maintained in the manner illustrated in the upper part of Fig. 5.

Clamped about the pipe 62 a short ways above the plate 72 are two clips 74. Bearing downwardly on the upper of these clips, but separated therefrom by a block 75 of electrical insulating material, is one end of the lever 76. The other end of the lever 76 rests on a support 77 extending upwardly from the canopy 22. Intermediate its ends the lever 76 is guided vertically by sliding along the pin 78 extending upwardly from the canopy.

The lever conveniently is forced downwardly by means of a helical spring 79 surrounding the upper end of the pin 78 and compressed between the lever and a washer and nut on the upper end of the pin. With such an arrangement a tight 55 connection is assured between the lower end of the pipe 62 and the plug 61.

Also secured to the pipe 62 by means of the clips 74 is an electrical lead 81 to permit connection of the pipe in an electrical circuit for heating purposes, as will be described more fully hereinafter.

The plate 66 secured on top of the canopy also has an opening into the annular space surrounding the pipe 62 within the canopy and ram of the 65 press. Secured in this opening is a pipe 82 which is connected to a vacuum pump, not shown. By means of this connection 82 the annular space within the canopy and ram around the pipe 62 may be evacuated.

Above the point where the clips 74 are attached the pipe 62 is bent from the vertical so that it slopes, preferably slightly upward, over the top of the press toward the molten metal container, for example the melting pot 87. Since, in the 75

illustrative embodiment, the pipe is to be heated electrically to insure free passage of molten metal therethrough from the container 87 to the press cylinder, the pipe desirably is covered throughout 5 its length between the press and the container 87 with a thick wall 83 of heat insulating material.

Secured to the pipe 62 over the upper end of the melting pot, as by means of a clip 84, is an electrical lead 85. Over the melting pot the pipe 10 62 is bent downwardly and passes through a stuffing box 86 in the upper end of the melting pot 87 into the pot. Conveniently this stuffing box 86 may be similar to the stuffing box surrounding the pipe 62 where it emerges from the 15 press canopy.

The pipe 62 desirably is one unbroken length extending from the point where it discharges into the press cylinder to the point where it is supplied with molten metal in the container 87. Where a 20 single length of pipe is used there is much less danger of a leak permitting access of air to the molten metal in its passage through the pipe. Also there is less danger of the pipe becoming clogged, since uniform heating of the pipe is 25 facilitated and can be more accurately controlled than would be the case if several lengths of pipe were used with elbows and couplings. It is necessary that the pipe 62 be heated above the melting point of the metal which is to be extruded so 30 that in passing from the melting pot to the press the metal will not freeze and block the pipe.

It will be noted that a portion of the pipe is surrounded by the press ram and canopy, that another portion of the pipe is exposed to the 35 atmosphere except for the insulation 83, and that a third portion of the pipe extends into the container of molten metal. These several sections of the pipe will need different amounts of heat to furnish a substantially uniform temperature 40 throughout the length of the pipe. Conveniently, the pipe is heated by passing electric current longitudinally therethrough, and suitable connections are shown diagrammatically in Fig. 1.

In this illustrative embodiment the pipe is 45 divided electrically into three sections. A source of electric current, for example a transformer 91, is connected by means of an electrical conductor 92 to the frame of the lead press, and by means of a conductor 93 to the electrical lead 81 secured 50 to the pipe 62 adjacent the point where it emerges from the press canopy. A second source of electric power, for example the transformer 94, is connected by means of a conductor 95 to the electrical lead 81 on the pipe 62, and by means of a 55 conductor 96 to the electrical lead 85 on the pipe 62. A third source of electrical power, for example the transformer 97, is connected by means of a conductor 98 to the electrical lead 85 on the pipe 62, and by means of a conductor 99 to the 60 metal melting pot 87. By regulating the currents flowing through each of these three sections of pipe it is possible to obtain a substantially uniform temperature throughout the length of the pipe.

65 One means for segregating a charge of molten metal in the pot 87 and for forcing this molten metal through the pipe 62 into the press cylinder is shown in section in Fig. 6. The pipe 62, passing downwardly through the stuffing box 86 in 70 the melting pot 87 terminates within the interiorly shouldered pipe 101 with a close sliding fit. The pipe 101 is secured at its lower end in the pump cylinder head 102. The pipe 101 connects by means of a passage 103 through the cylinder 75 head with the interior of the pump cylinder 104.

The interior of the pump cylinder 104 also is connected through the passageway 105 in the cylinder head, and the valve 106 to the interior of the melting pot 87. The valve 106 is opened and closed by means of the valve stem 107 extending upwardly through a stuffing box 108 in the top of the melting pot 87. The valve 106 has a horizontal opening therethrough, so that when the valve is turned to one position this opening registers with the passageway 105, and when the valve 10 is rotated 90 degrees this opening in the valve is crossways of the passageway 105, preventing flow of metal therethrough. The valve operating mechanism will be described more fully hereinafter. 15

The pump cylinder head 102 desirably is positioned within the melting pot 87 so that in the normal course of operation molten metal always will be withdrawn from a point at some distance from the walls of the pot 87 as well as at some 20 distance below the level of the metal. The level of metal in the pot will vary, of course, as molten metal is withdrawn and as new metal is added. Desirably the intake which supplies metal through the pipe 62 to the press is located far enough down 25 in the pot so that any dross formed on the metal surface will not be carried through the pipe 62 into the press. Desirably, the intake for the molten metal is located some slight distance above 30 the bottom and spaced from the walls of the pot to prevent transfer to the press of any impurities which may have accumulated or formed on the bottom or walls of the pot.

Mounted within the pump cylinder 104 is the piston 109, desirably fitted with piston rings 110. 35 Adjacent its upper end the cylinder 104 is provided with a plurality of ports 111 to permit entrance and exit of metal back of the piston as the piston moves up and down in the pump cylinder. The cylinder conveniently is secured at its upper 40 end to the top of the pot 87, for example by means of a cylindrical member 112 firmly secured in an opening in the top of the pot.

Extending upwardly from the piston 109 to which it is secured is the piston rod 113. The 45 piston rod 113 passes through the cylinder 104, a stuffing box 114 in the lower end of the member 112, and continues upwardly beyond the top of the melting pot. Formed on or secured to the upper end of the piston rod 113 is a gear rack 115. The piston and piston rod are movable vertically, and this movement is controlled by means of a pinion 50 116 engaging the rack 115.

The pinion 116 is rigidly secured on the shaft 55 117. One end of the shaft 117 is rotatably mounted in bearings on the upper end of a housing 118 rising from the top of the melting pot 87. Referring now to Fig. 1, the other end of the shaft 117 is rotatably mounted in a bearing, not shown, on the press canopy 22. Rigidly secured on the 60 shaft 117 adjacent the lead press is a sprocket 119. Engaging the sprocket 119 is a power transmission chain 120 which passes downwardly and around a sprocket 121 rotatably mounted near the bottom of the columns 21.

The ends of the sprocket chain passing around the sprockets 119 and 120 are connected by means of a screwthreaded link 122. Spaced apart on the link 122 are two sets of adjustable lock nuts 123 and 124. Engaging the link 122 between the 65 two sets of lock nuts is the forked end of a bracket 125 which is secured on the upper end of the hydraulic press plunger 31 so as to move up and down with the plunger.

70 It will be apparent that as the plunger 31 moves 75

up and down the bracket 125 will cause the sprocket chain 120 to move, thereby rotating the shaft 117. As the press cylinder 24 is moved upwardly during an extrusion operation the shaft 117 will be rotated so as to raise the piston 109, thereby filling the pump cylinder 104 with molten metal from the melting pot. When the press cylinder 24 reverses direction and moves downwardly, the piston 109 will move in the opposite direction to force the molten metal from the pump cylinder 104 through the pipe 62 into the press cylinder 24.

By spacing the sets of lock nuts 123 and 124 apart on the connecting link 122, a slight lost motion may be introduced so that molten metal is not forced from the pump into the press cylinder until the valve in the lower end of the press ram is fully opened. This lost motion also makes it possible to maintain any desired clearance, for example an inch, between the end of the ram and the surface of the molten metal during the charging operation.

One suitable mechanism for operating the valve 106 controlling the flow of molten metal into the pump cylinder 104 is shown in Figs. 6, 7 and 8. On the outer end of the shaft 117, spaced a short distance apart, are rigidly secured two ratchet wheels 131 and 132. Mounted on the shaft 117 between these ratchet wheels and free to turn about the shaft is a lever 133 having at its outer end a weight 134. Rotation of the lever 133 about the shaft 117 is limited by means of the ears 135 and 136, which engage a stop 137 in the top of the housing 118 as the lever turns to the right or left as viewed in Figs. 7 and 8.

Pivottally secured on opposite sides of the lever 133 are the pawls 138 and 139 which engage, respectively, the ratchet wheels 131 and 132. Referring to Fig. 8, rotation of the shaft 117 to the right when the lever 133 is turned to the left, as shown in dotted lines, causes the ratchet wheel 131, engaging the pawl 138 to turn the lever to the right. When the lever is carried past the vertical position the weight 134 on its outer end causes the lever to continue its turning movement to the right at a more rapid rate until the ear 135 engages the stop 137. During this more rapid turning movement the pawl 138 is lifted out of engagement with the pawl wheel 131 and is held out of engagement by the arm 140 fixed on the top of the housing 118 which engages the outer end of the pawl.

Referring to Fig. 7 it will be seen that as the shaft 117 turns to the left the ratchet wheel 132, in engagement with the pawl 139, causes the lever 133 to turn to the left. As the lever passes the vertical position the end weight 134 carries the lever quickly to the left until the ear 136 engages the stop 137, as shown in dotted lines. As the lever 133 turns to the left the pawl 139 is lifted out of engagement with the pawl wheel 132 and is held out of engagement by means of the arm 141 secured on the top of the housing 118.

Thus it will be seen that rotation of the shaft 117 in either direction approximately one eighth of a turn shifts the lever 133 from one limit of its range of movement to the other limit.

Also mounted on the shaft 117 adjacent its end is a sheave 142 which is secured to the lever 133 by means of the connection 143 so that the sheave will turn about the shaft 117 with the lever 133. Passing around the sheave 142 is the wire or cable 144. The wire 144 passes downwardly, changes direction about the sheave 145 rotatably mounted on the housing 118, and then

around the sheave 146 rigidly secured on the upper end of the valve stem 107. The valve stem 107 is pressed downwardly to force the valve 106 into its seat as by means of a helical spring 147 surrounding the valve stem 107 and compressed between the valve stem bearing 148 and a collar 149 secured on the valve stem 107.

From the foregoing description it will be apparent that upon rotation of the shaft 117 approximately one-eighth of a turn in one direction the valve 106 will be opened, and that upon rotation of the shaft 117 approximately one-eighth of a turn in the opposite direction the valve 106 will be closed. During the extrusion operation the valve 106 is open so that molten metal will be drawn into the pump cylinder 104 by means of the piston 109, and as the press cylinder moves away from the press ram the valve 106 is closed so that the molten metal segregated in the pump cylinder is forced by the piston through the pipe 62 into the press cylinder.

Desirably the diameter of the pump cylinder and the stroke of the pump piston are such that as metal is being extruded from the press an equivalent quantity of molten metal is being segregated within the pump cylinder. For example, the pump cylinder might have the same internal diameter as the press cylinder, and the pump piston might move through the same distance and at the same speed as the press cylinder. Under such conditions the pump always would contain the correct amount of molten metal for recharging the press, regardless of the amount of metal which may have been extruded from the press.

During the extruding operation a specific quantity of molten metal equivalent to the quantity of metal extruded is being segregated within a separate container, in this instance the pump. When the extrusion operation has been completed the press cylinder recedes from the press ram, and as it does so, the press cylinder is progressively charged with this metal which has been segregated in the separate container. By suitable adjustment of the lost motion connection between the press cylinder and the transmission chain which actuates the metal pump the flow of molten metal into the press may be delayed to maintain a clearance between the level of the metal and the end of the ram. When the charging of the press cylinder has been completed and the metal has cooled sufficiently to permit extrusion thereof the pump in the melting pot segregates the metal which will be required for the next charging of the press. This operation of the pump is fully automatic in response to relative movement between the press cylinder and ram. Desirably the space within the press cylinder under the stuffing box around the ram is evacuated, throughout the operation, and air or other gases do not have access to the metal at any time during the charging operation.

Splashing of the metal and the formation of irregular lumps in the press cylinder during the charging operation are greatly reduced by reason of the point and direction of discharge of the molten metal into the cylinder, as well as by reason of the fact that the molten metal falls through a much shorter distance in the cylinder. Since the cylinder is evacuated, the formation of gas bubbles or pockets is eliminated.

If the distance which the molten metal must rise in passing from the melting pot through the pipe 62 to the press cylinder is not too great,

the atmospheric pressure may be utilized to force molten metal from the melting pot into the evacuated press cylinder. In that case the pump disclosed in Fig. 6 and the operating mechanism therefor disclosed in Figs. 6, 7 and 8 may be omitted, and a valved inlet alone is required for the end of the pipe 62 within the container 87.

Such a valved inlet is shown in Fig. 9. An opening in the top of the melting pot 87 is closed 10 with a plate 151, conveniently held in place by means of screws 152. An aperture 153 in the plate 151 provides an entry-way for the valve stem, and surrounding this opening and depending from the plate is the tube 154. Conveniently 15 the tube 154 may be secured to the plate 151 by welding. Closing the lower end of the tube 154 is the valved inlet member 155 which may be held in place by means of screws 156. This valved inlet member 155 desirably is positioned 20 within the melting pot so that metal will be withdrawn from a point spaced from the walls of the container and below any dross which may form on the top of the metal.

Ports 157, conveniently in three walls of the member 155, provide an entrance for molten metal from the melting pot into the passageway 150 through the member 155. Flow of molten metal is controlled by means of the valve 158 and a cooperating valve seat in the passageway 30 150 through the member 155.

The valve stem 159 extends upwardly through the tube 154 beyond the top of the melting pot, and conveniently may be rotated manually to open and close the valve. When the valve is open 35 molten metal may pass through the ports 157, the passageway 150 in the member 155, and the pipe 160 into the tube 62. Conveniently the pipe 160 is interiorly shouldered, and the end of the pipe 62 slides into the pipe 160 against this 40 shoulder. The pipe 62 passes upwardly through a stuffing box 163 in the plate 151, and thence to the extrusion press in the manner shown in Fig. 1.

During the extrusion operation the valve in the lower end of the press ram is closed, and the 45 valve 158 in the melting pot also is closed. As the press cylinder moves away from the ram after the charge in the press cylinder has been evacuated throughout this operation, as by means of the 50 pipe connection 38, and when the valve 158 is opened molten metal is forced by the atmospheric pressure from the melting pot through the pipe 62 into the press cylinder.

In extrusion presses where it is not possible to 55 see the level of metal in the press cylinder during a charging operation, as for example where the arrangement shown in Fig. 9 is used for controlling the flow of molten metal into the press cylinder, it is desirable to have a continuously operating indicator to indicate the amount of metal extruded from the press during an extrusion operation, and also the amount of molten metal supplied to the press during a charging operation. Suitable measuring and indicating apparatus for this purpose is shown, more or less diagrammatically, in Figs. 10 and 11.

Referring first to Fig. 10, a wire or cable 171 is fastened at one end to the movable member 70 of the press, for example to the bracket 125 shown in Fig. 1. This wire passes upwardly, changes direction around the sheaves 172 and 173, and then passes downwardly, making several turns around the windlass 174, and has secured 75 on its lower end the counterweight 175.

The windlass 174 is mounted so as to turn freely about a stud 176 secured at one end in the support 177.

Secured to the support 177, as at 178, and in front of the windlass 174 is a dial 179. This 5 dial is shown in front elevation in Fig. 11. The hub of the windlass 174 projects through the central opening in the dial 179 and has secured thereto the hand 180. It will be apparent that as the press cylinder moves up or down the extent of this movement will be indicated on the dial 179 by means of the hand 180.

Within the melting pot is a float 181 which moves up and down as the level of molten metal 15 in the pot varies. Conveniently this float may be guided in its movement by the vertically extending arm 184 passing upwardly through the top of the melting pot and engaging the guides 182 and 183 fastened to the melting pot.

Secured to the float guide, as at 185, is one 20 end of a wire or cable 186. The wire 186 passes upwardly, changes direction around the sheaves 187 and 188, and then passes downwardly and is secured at its end to one end of a gear rack 189. Fastened to the lower end of the gear rack 25 is a counterweight 195. Engaging the rack 189 is a pinion 190, rigidly secured on one end of the shaft 191 passing through the stud 176 to the face of the dial 179.

Secured to the end of the shaft 191 adjacent 30 the dial face is a hand 192. Desirably this hand is secured to the shaft 191 so that normally it will turn with the shaft, but so that it may readily be adjusted relative to the shaft. Such a connection may comprise the screw 193 in the 35 end of the shaft, and a helical spring 194 compressed between the head of the screw and the hand 192. It will be apparent from the foregoing description that any variation in the level of the molten metal in the melting pot will be 40 indicated on the dial face by means of the hand 192.

Desirably the scale on the dial 179 and the diameter of the windlass 174 are chosen so that the hand 192 records directly the vertical movement of the press cylinder in inches. The 45 diameter of the pinion 190 desirably is chosen so that the drop in the level of molten metal in the melting pot while the cylinder is being charged with molten metal will be indicated by the hand 192 directly in terms of the number of inches which the level of metal in the press cylinder is raised. With this arrangement the amount of metal extruded during an extrusion operation is continuously indicated, as is also 55 the amount of metal added to the press during a charging operation.

The time required for recharging the press may be reduced by permitting molten metal to enter the press as the press cylinder recedes from 60 the ram. During this operation a clearance, usually about one inch in lead presses, desirably is maintained between the end of the ram and the level of the molten metal, and this clearance may be accurately and conveniently controlled 65 with the mechanism described.

For example, when the press cylinder has reached the top of its stroke, that is at the end of the extrusion operation, the hand 192 is set one inch ahead of the hand 180, for example as 70 shown in Fig. 11. When the press cylinder recedes one inch, the valve in the melting pot being closed, the hand 180 has been moved until it is directly under the hand 192. At this point the inlet valve within the melting pot is opened 75

to permit molten metal to flow through the pipe 62 into the press cylinder. The amount by which this valve is opened is adjusted so that as the hand 180 continues to move around the dial, the hand 192 is kept directly over the hand 180. With this arrangement the molten metal will follow up the receding ram in the press cylinder and maintain the desired clearance between the end of the ram and the molten metal.

10 Applicant has provided improved apparatus whereby metal sheaths may be extruded about electrical cables, and in which oxidation of the metal during the extruding operation is prevented. Splashing of the metal and formation 15 of gas pockets in the charge are greatly reduced. Furthermore, introduction of impurities into the metal during the press charging operation is prevented, and the time required between extruding operations for charging the press is substantially shortened. This economy in time is 20 made possible by progressively charging the press cylinder with molten metal as the cylinder and ram separate, and also by accurately controlling the temperature of the molten metal as it enters 25 the cylinder.

It will be understood that the present invention may be variously modified and embodied within the scope of the subjoined claims.

I claim:

30 1. In apparatus for extruding solidified metal the combination of a cylinder, a die block connected to one end of said cylinder, said die block having a transverse die opening therein, a ram having an opening extending longitudinally 35 therethrough, said ram extending into the other end of said cylinder, sealing means between the cylinder and the ram preventing the entrance of air into the cylinder around the ram while permitting relative movement therebetween, means 40 for charging the cylinder with molten metal through the longitudinal opening in the ram, and means for causing relative movement between the cylinder and the ram to extrude the metal from the cylinder after it has solidified.

45 2. In apparatus for extruding solidified metal the combination of a cylinder, a die block connected to one end of said cylinder, said die block having a transverse die opening therein, a ram having an opening extending longitudinally 50 therethrough, said ram extending into the other end of said cylinder, sealing means between the cylinder and the ram preventing the entrance of air into the cylinder around the ram while permitting relative movement therebetween, means 55 for charging the cylinder with molten metal through the longitudinal opening in the ram, means for causing relative movement between the cylinder and the ram to extrude the metal from the cylinder after it has solidified, 60 and a valve mounted in the inner end of said ram preventing flow of molten metal outwardly from the cylinder through the longitudinal opening in the ram.

65 3. In apparatus for extruding solidified metal the combination of a cylinder, a die block connected to one end of said cylinder, said die block having a transverse die opening therein, a ram having an opening extending longitudinally 70 therethrough, said ram extending into the other end of said cylinder, sealing means between the cylinder and the ram preventing the entrance of air into the cylinder around the ram while permitting relative movement therebetween, means 75 for charging the cylinder with molten metal through the longitudinal opening in the ram,

means for causing relative movement between the cylinder and the ram to extrude the metal from the cylinder after it has solidified, a valve in said opening adjacent the lower end of the ram, and means which, during the course of normal operation, causes said valve to open automatically in response to movement of the cylinder relative to the ram in one direction and to close automatically in response to movement of the cylinder relative to the ram in the opposite direction.

4. In apparatus for extruding solidified metal the combination of a cylinder, a die block connected to one end of said cylinder, said die block having a transverse die opening therein, a ram having an opening extending longitudinally therethrough, said ram extending into the other end of said cylinder, means for causing relative movement between the cylinder and the ram, sealing means between the cylinder and the ram preventing the entrance of air into the cylinder around the ram while permitting relative movement therebetween, and means for progressively 15 charging the cylinder with molten metal through the longitudinal opening in the ram as the ram moves outwardly relative to the cylinder after the preceding charge has been extruded.

5. In apparatus for extruding solidified metal the combination of a cylinder, a die block connected to one end of said cylinder, said die block having a transverse die opening therein, a ram having an opening extending longitudinally therethrough, said ram extending into the other end of said cylinder, means for causing relative movement between the cylinder and the ram, sealing means between the cylinder and the ram preventing the entrance of air into the cylinder around the ram while permitting relative movement therebetween, means for progressively 30 charging the cylinder with molten metal through the longitudinal opening in the ram as the ram moves outwardly relative to the cylinder, and means which in the normal course of operation controls the flow of molten metal into the cylinder 35 automatically in response to relative movement between the cylinder and the ram.

6. In apparatus for extruding solidified metal the combination of a cylinder, a die block connected to one end of said cylinder, a ram having an opening extending longitudinally therethrough, said ram extending into the other end of said cylinder, sealing means between the cylinder and the ram preventing the entrance of air into the cylinder around the ram while permitting relative movement therebetween, means 50 for charging the cylinder with molten metal through the longitudinal opening in the ram, means for causing relative movement between the cylinder and the ram to extrude the metal 55 from the cylinder after it has solidified, means for measuring and indicating continuously the amount of metal extruded during an extrusion operation, and means for measuring and indicating continuously the amount of metal which enters the cylinder during a charging operation.

7. In apparatus for extruding solidified metal the combination of a cylinder, a die block connected to one end of said cylinder, a ram having an opening extending longitudinally therethrough, said ram extending into the other end of said cylinder, sealing means between the cylinder and the ram preventing the entrance of air into the cylinder around the ram while permitting relative movement therebetween, a con- 70

tainer for molten metal, means for charging the cylinder with molten metal from said container through the longitudinal opening in the ram, means for causing relative movement between the cylinder and the ram to extrude the metal from the cylinder after it has solidified, and means operating automatically and continuously in response to extrusion of metal from the cylinder for measuring off and segregating an equivalent 10 charge of molten metal for the cylinder.

8. In a metal extruding apparatus the combination of a cylinder, a die block connected to one end of said cylinder, a ram having an opening extending longitudinally therethrough, said ram 15 extending into the other end of said cylinder, sealing means between the cylinder and the ram preventing the entrance of air into the cylinder around the ram while permitting relative movement therebetween, a container for molten metal, means for charging the cylinder with molten metal from said container through the longitudinal opening in the ram, means for causing relative movement between the cylinder and the ram to extrude metal from the cylinder, means operating 20 automatically in response to relative movement between the cylinder and the ram during extrusion of metal from the cylinder for measuring off and segregating in said container an equivalent charge of molten metal for the cylinder and operating automatically in response to relative movement between the cylinder and the ram in the direction opposite to that for extruding metal for delivering said charge of molten metal to the cylinder.

9. In apparatus for extruding solidified metal the combination of a cylinder, a die block connected to one end of said cylinder, a ram extending into the other end of said cylinder, means for charging the cylinder with molten metal, means for causing relative movement between the cylinder and the ram to extrude the metal from the cylinder after it has solidified, means for measuring and indicating continuously the amount of metal extruded during an extrusion 40 operation, and means for measuring and indicating continuously the amount of metal which enters the cylinder during a charging operation.

10. In a metal extruding apparatus the combination of a cylinder, a die block connected to one end of said cylinder, a ram extending into the other end of said cylinder, a container for molten metal, means for charging the cylinder with molten metal from said container, means for causing relative movement between the cylinder and the ram to extrude metal from the cylinder, and means operating automatically in response to relative movement between the cylinder and the ram during the extrusion of metal from the cylinder for measuring off and segregating an equivalent charge of molten metal for the cylinder.

11. In a metal extruding apparatus the combination of a cylinder, a die block connected to one end of said cylinder, a ram extending into the other end of said cylinder, a container for molten metal, means for charging the cylinder with molten metal from said container, means for causing relative movement between the cylinder and the ram to extrude metal from the cylinder, means operating automatically in response to relative movement between the cylinder and the ram during extrusion of metal from the cylinder for measuring off and segregating in said container an equivalent charge of molten metal for the cylinder and operating automatically in re-

sponse to relative movement between the cylinder and the ram in the direction opposite to that for extruding metal for delivering said charge of molten metal to the cylinder.

12. In apparatus for extruding solidified metal 5 the combination of a cylinder, a die block connected to one end of said cylinder, a ram extending into the other end of said cylinder, sealing means between the cylinder and the ram preventing the entrance of air into the cylinder 10 around the ram while permitting relative movement therebetween, means for charging the cylinder with molten metal through a longitudinal opening in the ram, means for causing relative movement between the cylinder and the ram to 15 extrude the metal from the cylinder after it has solidified, and means for evacuating the space between the cylinder and the ram under the said sealing means.

13. In apparatus for extruding solidified metal 20 the combination of a cylinder, a die block connected to one end of said cylinder, a ram extending into the other end of said cylinder, sealing means between the cylinder and the ram preventing the entrance of air into the cylinder around 25 the ram while permitting relative movement therebetween, means for causing relative movement between the cylinder and the ram to extrude the metal from the cylinder after it has solidified, and means for measuring and indicating 30 continuously the amount of metal extruded from the cylinder during an extrusion operation.

14. In apparatus for extruding solidified metal the combination of a cylinder, a die block connected to one end of said cylinder, a ram having 35 an opening extending longitudinally therethrough, said ram extending into the other end of said cylinder, means for charging the cylinder with molten metal through the longitudinal opening in the ram, means for causing relative movement between the cylinder and the ram to extrude metal from the cylinder, a valve in said 40 opening at the inner end of said ram, and a valve operating mechanism secured to said valve and extending beyond the end of the ram into and 45 terminating in the cylinder.

15. In a metal extruding apparatus the combination of a cylinder, a die block connected to one end of said cylinder, a ram having an opening extending longitudinally therethrough, said 50 ram extending into the other end of said cylinder, means for causing relative movement between the cylinder and the ram, means for charging the cylinder with molten metal through the longitudinal opening in the ram, said means comprising a metal pipe smaller than the longitudinal opening through the ram extending from the inner end of the ram outwardly through the longitudinal opening therein, and means for 55 evacuating the space in said opening exteriorly 60 of said pipe.

16. In a metal extruding apparatus the combination of a cylinder, a die block connected to one end of said cylinder, a ram having an opening extending longitudinally therethrough, said 65 ram extending into the other end of said cylinder, means for causing relative movement between the cylinder and the ram, means for charging the cylinder with molten metal through the longitudinal opening in the ram, said means comprising a metal pipe extending from the inner end of the ram outwardly through the longitudinal opening therein, and means for heating said pipe 70 electrically throughout its length.

17. In a metal extruding apparatus the com- 75

- bination of a cylinder, a die block connected to one end of said cylinder, a ram having an opening extending longitudinally therethrough, said ram extending into the other end of said cylinder, 5 means for causing relative movement between the cylinder and the ram, means for charging the cylinder with molten metal through the longitudinal opening in the ram, said means comprising a metal pipe extending from the inner 10 end of the ram outwardly through the longitudinal opening therein, and an electrical connection between the pipe and the ram adjacent the inner end of the ram, said pipe and ram being otherwise insulated electrically one from 15 the other.
18. The combination with a press for extruding a metal sheath on an electrical cable, said press comprising a cylinder, a die block connected to one end of said cylinder, a ram having an 20 opening longitudinally therethrough extending into the other end of the cylinder, and means for causing relative movement between the cylinder and the ram, of a container for the molten metal with which the press is to be charged, and means 25 for charging the press with molten metal from the container, said means comprising a continuous one-piece pipe extending from a point in the container below the level of the metal and spaced from the walls of the container through 30 the longitudinal opening in the ram to a point where it discharges directly into the press cylinder.
19. The combination with a press for extruding solidified metal, said press comprising a cylinder, a die block connected to one end of said cylinder, a ram having an opening longitudinally therethrough extending into the other end of the cylinder, and means for causing relative 35 movement between the cylinder and the ram of a container for the molten metal with which the press is to be charged, means for charging the press with molten metal from the container, said means comprising a one-piece metal pipe extending from the container through the longitudinal opening in the ram to a point where it 40 discharges directly into the press, and means for 45
- passing an electric current longitudinally through the pipe to maintain the pipe temperature sufficiently high to prevent the molten metal from congealing while flowing through the pipe.
20. The combination with a press for extruding solidified metal of a container for the molten metal with which the press is to be charged, and means operating automatically and continuously in response to extrusion of metal from the press to segregate an equivalent quantity of molten 10 metal in the container.
21. The method of operating apparatus for extruding metal sheaths on electrical cables, said apparatus comprising a cylinder, die block and ram, which method comprises effecting relative 15 withdrawal movement between the cylinder and the ram to permit charging of the cylinder with molten metal, discontinuing such movement while the cylinder still engages the end of the ram, charging the cylinder with molten metal 20 free from gas and other impurities, permitting the molten metal to cool and solidify, applying suction to the top of the metal in the cylinder to remove from the cylinder during the charging and cooling operations any gas which may 25 have been entrained in the molten metal, and effecting relative movement between the cylinder and the ram to extrude the solidified metal through the die block.
22. The method of charging the cylinder of a 30 press for extruding metal sheaths on electrical cables with molten metal from a molten metal container, which method comprises withdrawing molten metal from the container at a point below the dross line and spaced from the walls of the 35 container, conveying the metal so withdrawn to the press and charging the press cylinder therewith, preventing access of air to the molten metal in its passage from the container to the press cylinder, and applying suction around the ram 40 and in the upper portion of the cylinder to remove from the cylinder during the charging operation any gas which may have been entrained in the molten metal.

EDGAR W. MACKNIGHT.
